UNITED STATES PATENT OFFICE.

MICHEL FRANCES BRODERICK, OF OBERLIN, KANSAS.

HARNESS ATTACHMENT.

SPECIFICATION forming part of Letters Patent No. 642,072, dated January 30, 1900.

Application filed July 6, 1896. Serial No. 598,174. (No model.)

To all whom it may concern:

Be it known that I, MICHEL FRANCES BRODERICK, a citizen of the United States, residing at Oberlin, in the county of Decatur and 5 State of Kansas, have invented a new and useful Harness Attachment, of which the following is a specification.

This invention aims to provide for the lengthening and shortening of the traces or 10 tugs in a simple and convenient way and to provide against the wear between the connection of the traces and the loops or bolts of the hames or breast-iron.

A further purpose of the invention is to devise a buckle which can be readily and quickly 15 adjusted along a trace or tug when it is required to lengthen or shorten the latter, one end of the buckle being constructed so as to admit of the buckle being moved to disconnect its tongue from the meeting parts of the trace.

A still further purpose of the invention is to interpose a wear-strap between the fold of the trace and the loop or bolt by means of 25 which the trace is connected to the hames or breast-iron, said wear-strap having side loops to receive the folded portions of the trace, so as to hold them close together.

For a full understanding of the merits and 30 advantages of the invention reference is to be had to the accompanying drawings and the following description.

The improvement is susceptible of various 35 changes in the form, proportion, and the minor details of construction without departing from the principle or sacrificing any of the advantages thereof, and to a full disclosure of the invention an adaptation thereof is shown in the accompanying drawings, in 40 which—

Figure 1 is a perspective view of a hame and trace, showing the application of the invention. Fig. 2 is a detail view showing the relative position of the buckle when the 45 end portion of the trace is released, so as to admit of the trace being lengthened or shortened. Fig. 3 is a perspective view of the buckle, showing the latch-bar locked. Fig. 4 is a detail view of the wear-strap.

Corresponding and like parts are referred to in the following description and indicated

in the several views of the drawings by the same reference characters.

The hame 1 and trace 2 are of ordinary construction and are shown to illustrate the application of the invention. The end portion of the trace is folded and passes through a box-loop 3 and through a loop 4, secured to the hame, the loop 4 being of usual construction and, as shown, consisting of a bolt passing through apertured lugs extending from the hame.

The buckle for securing the end of the trace comprises a plate 5 and end loops 6 and 7, the loop 6 being closed and the loop 7 open at its outer end and adapted to be closed by a latch-bar 9, which is pivoted at one end to a side bar of the loop and has its opposite end constructed to interlock with the terminal of the opposite side bar. The side bar of the loop 7, with which the latch-bar interlocks, has its terminal bent, forming a lip 10, which engages over the outer side of the latch-bar 9 and holds the latter locked. The latch-bar 9 has a tendency to spring behind the lip 10 and is held in engagement with the latter by this spring tendency, and the free end of the latch-bar is bent or rolled, forming a projection 11 to be engaged by the finger or thumb when it is required to disconnect the latch-bar to free the loop 7 from the trace. This construction is shown most clearly in Fig. 2. A tongue or stud 12 projects from the plate 5 and is adapted to pass through corresponding openings in the trace and the end thereof, so as to secure the end of the trace and the buckle in the required position.

The wear-strap 13 is formed of a short length of harness-leather, which is doubled upon itself, forming a sleeve 14 to receive the closed end of the loop 4 or the bolt by means of which the trace is connected to the hame, and the end portions of the leather are stitched together. Opposite loops 15 form a part of the wear-strap and are provided by cutting parallel slits in the end portions of the strap and deflecting the part coming between the slits, substantially as shown. This wear-strap is wider than the trace or tug, so as to prevent injurious contact of the trace with the loop or iron with which it is connected. The trace passes through one of the loops 15, thence

through the loop 4, around the wear-strap, and back through the opposite loop 15, thence through the box-loop 3, and through the loops 6 and 7 of the buckle. When it is required 5 to lengthen or shorten the trace or tug, the buckle is loosened by freeing the latch-bar and is moved away from the trace, so as to withdraw the tongue or stud 12 from engagement with the trace, after which the end portion 10 of the latter can be moved to the required position, when the tongue or stud 12 will be thrust through registering openings and the latch-bar 9 will be turned so as to cause the loop 7 to embrace the trace and the 15 end portion thereof, substantially as shown in Fig. 1, thereby holding the parts in the adjusted position.

Having thus described the invention, what is claimed as new is—

In harness, a wear-strap folded upon itself 20 intermediate of its ends and having transverse slits formed in the folded end portions, and having the parts between the said slits deflected outwardly to form side loops integral with the wear-strap, substantially as set 25 forth.

In testimony that I claim the foregoing as my own I have hereto affixed my signature in the presence of two witnesses.

MICHEL FRANCES BRODERICK.
